DOOR CHECK AND CLOSER.

1,247,274.

Specification of Letters Patent. Patented Nov. 20, 1917.

Application filed March 14, 1917. Serial No. 154,781.

To all whom it may concern:

Be it known that I, JOHN HOFERLE, a citizen of the United States, and a resident of the city of Chicago, county of Cook, and 5 State of Illinois, have invented certain new and useful Improvements in Door Checks and Closers, of which the following is a specification.

My invention relates to automatic door 10 closing and checking devices that are adapted to be carried partly by the door and partly by the casing surrounding the same in a manner similar to that disclosed in Letters Patent of the United States issued to 15 me under date of March 30, 1915, No. 1,133,725, for an improved "door check and closer." In a device of this character the door is closed by means of a suitable contraction spring inclosed within the cylinder 20 and hollow piston rod and is checked or retarded in its movement through the medium of a cushion of air or other fluid, in order to avoid the slamming of the door.

One of the objects of my present invention 25 is to provide a door closing device of this character with means whereby the tension upon the retractable spring may be readily adjusted without the necessity of removing the piston from the cylinder or dis- 30 assembling the device.

Another object of my device is the provision of a novel piston head that is constructed in a manner so that the air may pass easily through the piston head and the 35 piston from one side to the other as the door is opened, but will be compressed in front of the piston head as the door is closed and will thereby check or retard the closing of the same.

40 A further object of my present invention is the provision in a door closing and checking device of suitable novel means for retaining the flexible ring or washer of the piston head in close contact with the interior 45 of the cylinder and prevent leakage of air around the same.

Other objects of my invention comprise 50 the provision of a door closing and checking device that is comparatively simple in construction, economical to manufacture, and dependable in its operation.

I prefer to accomplish the divers objects 55 of my invention by substantially the means and in substantially the manner hereinafter fully set forth and described, reference be-

ing had to the accompanying drawings forming a part of this specification, wherein,—

Figure 1 is a top plan of my closing and 60 checking device attached to a door and casing, the door being partly opened for the purpose of illustrating the relative positions of the elements of my device.

Fig. 2 is a longitudinal front elevation 65 thereof.

Fig. 3 is a central longitudinal section taken through the cylinder, piston rod, and piston head.

Fig. 4 is a fragmental section showing the 70 parts of the piston head in the relation assumed during a compression stroke.

Fig. 5 is a transverse section on line 5—5 of Fig. 4, particularly showing an arrangement of the spring for expanding the cup-washer.

Fig. 6 is a perspective view showing a 75 modified structure for expanding the cup-washer.

In the drawings similar reference characters have been employed to designate the 80 same parts throughout the divers figures thereof.

Referring more particularly to Figs. 1, 2 and 3 of the drawings, it will be observed 85 that the device preferably comprises an elongated cylinder or tubular member 10, wherein a suitable hollow piston rod 11 is adapted to reciprocate while a coiled contraction spring 12 is inclosed in said piston rod, one end of said spring being adapted to extend out 90 through the inner end of hollow piston rod 11 and is connected to the closure cap 13 screwed or otherwise secured to the adjacent end of the cylinder 10. The opposite end of 95 said spring is connected by an elongated bolt 14 to the opposite or outer end of the piston rod 11, said bolt being provided with a flat sided or squared shank 15 that fits into a correspondingly shaped opening 16 in a washer 17 disposed in the end of the piston 100 rod. In order that the head of the bolt may be conveniently seated in the washer, the latter is preferably constructed in a concave manner, as shown, so that when the cap 18 of said piston rod is screwed onto the end 105 thereof, it will press against said washer and thereby prevent the rotation of the bolt 14. The elongated threaded portion of the bolt is tapped or screwed into a round or cylindrical nut 19 that is frictionally held 110

- in the adjacent end of the coiled spring 12, and it will be observed that by releasing the cylinder 10, and rotating the same in the one direction or the other relative to the piston rod, the nut 19 will be screwed up or down on the bolt 14, thereby extending or contracting the spring 12, and cause the same to exert greater or less tension in closing the door.
10. The cap 13 is provided with a suitable embossment 20, that provides means whereby the adjacent end of the cylinder may be pivotally and removably mounted upon the hinge of a suitable toggle, one of the members whereof comprises a horizontally disposed substantially L-shaped arm 21 that has the upper end of its lateral portion 22 screw-threaded to form a pinte that receives the lug or embossment 20 of cap 13.
15. The opposite end of arm 21 is hingedly connected to a mounting plate 23 secured in any suitable manner to the upper portion of the door and which is so positioned that said arm will, under normal conditions, be disposed in a plane at substantially a right-angle to the plane of the door when closed. The companion member of the toggle consists of an extensible or adjustable link, one element 24 of which is pivotally secured to
20. a bracket 25 mounted on the door frame and comprises a turn-buckle that is adapted to coöperate with the elongated threaded shank of the other element 26 of said link. The outer end of the link is preferably bent or deflected laterally and is adapted to be adjustably and pivotally mounted in a bifurcated lateral boss 27, formed on one side of the shorter vertical portion 22 of the L-shaped arm 21. This disposition of the
25. toggle and its connected elements will permit the door to be opened and closed in the customary manner or to be swung back until the pull of the spring is on an approximate dead-center, when the energy of the same will not be felt and the door will remain in opened position.
- I have disclosed herein a novel construction of the piston carried upon the inner end of the hollow piston rod 11, which is illustrated in detail in Figs. 3, 4 and 5, of the drawings, wherein it will be observed an annular shoulder 28 is provided upon the inner end of the piston rod. A flared sleeve 29 of substantially the same diameter as the piston rod is screwed into the threaded bore of said shoulder or piston rod in the former instance until it abuts the end of the piston rod as shown in Figs. 3 and 4 and this flared sleeve extends through a central aperture in the valve or piston head to be hereafter described. The flared sleeve 29 has lateral ports 30 provided therein and a packing washer or gasket 31 is interposed between the shoulder 28 and the base of the
30. valve or piston head. When the piston head or valve is entering the cylinder 10, the base thereof will be forced against the washer 31 which in its turn will be forced against the annular shoulder 28, thereby preventing the escape of air from one side of the valve or piston head to the other; but when the piston is being withdrawn in the cylinder 10, the piston head or valve will move forward to the flared end portion of the sleeve 29, thereby uncovering the ports 30 and permitting a free passage of the air through the piston head or valve, which greatly facilitates the withdrawal of the piston and the opening of the door.
- The piston head or valve preferably comprises a base plate 32, centrally punched to provide an annular flange 33 that surrounds the flared sleeve 29. A cup-washer 34 of leather or other suitable material, is mounted upon the base-plate about the flange 33 and is secured thereto by a flat ring 35 over which the edge of the flange 33 is up-set. In order to keep the sides of the cup-washer in yielding and coöperative relation with the walls of the cylinder 10, I have provided the spring-ring 36, which is held inside of the cup-washer by tongues 37, extending from the flange of base-plate 32 inside the cup-washer and outside and over the spring ring as shown. As a modified means for pressing the cup-washer into contact with the cylinder 10, I have provided a flat ring 38, shown in detail in Fig. 7 of the drawings, which has a series of spring tongues 39, extending laterally from the outer edge thereof which are adapted to press against the interior surface of the cup-washer. The assembly of the head of bolt 14 with concave washer 17, while being sufficiently close to prevent a rotation, is not, however, so tight as to prevent the easy passage of air past the same.
- What I claim as new is:
1. A door check and closer comprising a cylinder, a hollow piston-rod reciprocable therein, and provided with lateral ports, a spring within said cylinder and piston-rod one end, whereof is connected to the adjacent end of said cylinder, a piston-head movably mounted upon the inner end of said piston-rod and adapted to control the passage of air through said ports, and a bolt carried by said piston-rod to which the adjacent end of said spring is adjustably connected. 110
  2. A door check and closer comprising a cylinder, a hollow piston rod reciprocable therein, a spring within said cylinder and piston-rod one end, whereof is connected to the adjacent end of said cylinder, a bolt carried by said piston-rod, an element adjustable upon said bolt to which the adjacent end of said spring is connected whereby the rotation of said cylinder is adapted to regulate the tension of said spring. 120
  3. In a door checking and closing device 130.

comprising a cylinder and a hollow piston-rod, and means for retracting said rod within said cylinder, a piston-head movably mounted upon said rod, and valve mechanism controlled by the movement of said piston-head and coöperating with said hollow piston-rod whereby the fluid in said cylinder is adapted to pass from one side to the other of said piston-head through said 10 piston-rod.

4. In a door checking and closing device comprising a cylinder and piston-rod, and means for retracting said rod within said cylinder, a piston-head carried by the inner

end of said rod, a cup-washer mounted upon 15 said piston-head, a spring mounted within said cup-washer and adapted to press the walls thereof into contact with said cylinder and a device carried by a portion of said washer and adapted to retain said spring in 20 position against said washer.

Signed at Chicago, county of Cook, and State of Illinois, this 10th day of March, 1917.

JOHN HOFERLE.
